UNITED STATES PATENT OFFICE.

FRANK J. BAUMAN, OF DETROIT, MICHIGAN, ASSIGNOR OF ONE-THIRD TO HARRY M. LAU AND ONE-THIRD TO DELBERT M. WHITE, BOTH OF DETROIT, MICHIGAN.

PROPELLED MECHANISM FOR AIRPLANES.

1,307,721.

Specification of Letters Patent. Patented June 24, 1919.

Application filed January 17, 1918. Serial No. 212,321.

To all whom it may concern:

Be it known that I, FRANK J. BAUMAN, a citizen of the United States, residing at Detroit, in the county of Wayne and State of Michigan, have invented a new and useful

Propelling Mechanism for Airplanes, of which the following is a specification.

This invention relates to machines for aerial navigation and particularly to means

for propelling such machines.

The main object of the invention is to provide improved driving mechanism especially adapted for machines of the bi-plane type, by which the machine may be caused to rise from the ground more abruptly than usual and within a comparatively shorter initial running space, and which may be so controlled in descending as to enable a safe landing of the machine within such limited

space.

The invention in attaining this object contemplates the provision of manually controlled means, in connection with the transmission of power from the engine to the main propeller, by which the propeller shaft may be swung vertically in the arc of a circle to tilt the propeller angularly relative to the planes of the machine so as to vertically deflect the driving force and course thereof, and also to provide for operation in conjunction with the above means an auxiliary horizontally rotatable propeller mounted upon a vertical axis intermediate the ends of the machine and the upper and lower planes thereof for exerting lifting force thereon in a vertical direction, together with manually controlled means for effecting a releasable driving connection with the engine to enable the auxiliary propeller to be driven in unison with the main propeller particularly when operating in its angular positions of adjustment as when ascending or descending and to be disengaged as when the machine is in flight with the main propeller operating in the normal position.

In carrying out the present invention I have illustrated in the accompanying drawings one embodiment of the essential features by which the above objects are attained, in connection with which certain structural features relating to the planes and body of the machine as shown are substantially the same as is disclosed in a co-pending application for patent filed by me

January 4, 1918, under Serial No. 210,356, and which are not included herewith further than to illustrate the application of the present invention thereto.

In the drawings,

Figure 1 is a central vertical longitudinal section through the body of a bi-plane equipped with my improved propelling means.

Fig. 2 is a horizontal longitudinal section on dashed line 2—2 of Fig. 1.

Referring to the parts of the device by the characters of reference on the drawings, 1 designates in general the frame-work or body of a bi-plane which may be of any suitable or known form and the particular structural arrangement herein shown forms the subject matter of a co-pending application before referred to and need not be described herein other than in general terms.

Mounted in the forward end of the body 2 of the lower portion of the machine is an engine 3 having a rearwardly extending crank case terminating in an inclosed gear case 4 into which the crank shaft 5 of the engine extends. Extending vertically from the gear case 4 is a tubular standard or sleeve 6 in which is journaled to rotate about a vertical axis a shaft 7 which extends at its lower end into the gear case 4 and carries a fixed thereon a beveled gear 8 in mesh with a beveled gear 9 fixed on the engine shaft 5. The upper end of the vertical shaft 7 extends into a cylindrical gear case 10 formed on the upper end of the sleeve 6, and fixed on this end of said shaft is a beveled pinion 11 in mesh with a gear 12 loosely mounted to rotate upon a horizontal rock shaft 13 which is journaled at opposite ends respectively in bearings 14 formed in the ends of the gear case 10. See Fig. 2.

Mounted in a peripheral opening 15 in the wall of the cylindrical gear case 10 is a bearing box 16 having arcuate grooves 17 in opposite edges thereof which receive the respective walls of said opening and slidably retain said bearing box therein, and journaled in this bearing box and extending centrally into the gear case 10 is the main propeller shaft 18, the inner end of which extends through and is secured to rotate in the rock shaft 13. The outer end of the propeller shaft 18, which carries the main propeller 19, is supported in a journal bearing 20 which is mounted to slide in a guide-way 21.

- formed in an arcuate support 22 arranged concentric to the axis of the rock shaft 13, and fixed upon this shaft within the gear case 10 is a beveled gear 23 in mesh with a 5 pinion 24 fixed on a control shaft 25 which extends from said casing to a point adjacent the driver's seat 26, and carries a hand wheel 27 through the rotation of which motion is imparted to turn the rock-shaft and swing 10 the propeller shaft and its bearings vertically in the arc of a circle concentric with the axis of said rock-shaft. The power transmitted from the engine shaft to the vertical shaft 7 is imparted to drive the propeller shaft in any of its positions of adjustment through a beveled pinion 28 fixed on the end thereof within the gear case 10 and meshing with the gear 12 loosely carried by the rock-shaft 13.
- 15 20 When the main propeller is raised to operate in an angular position relative to the planes of the machine, as indicated by dotted lines in Fig. 1, it is apparent that the lifting power exerted by the propeller will 25 raise the forward end of the machine in advance of the rear portion tending to turn or tilt it vertically, and in order to prevent such undue tilting and to provide for counter-balancing and raising the tail of the machine in unison with the forward portion so as to enable a comparatively abrupt 30 ascent of the machine bodily to be made without materially affecting its substantially horizontal normal position, I provide at or 35 near the rear of the machine, and preferably between the upper and lower planes thereof, a horizontally rotatable auxiliary propeller 29 which is fixed upon a shaft 30 journaled to rotate vertically in bearings 31 mounted 40 on the frame of the machine. The lower end of this shaft is provided with a beveled gear 32 in mesh with a beveled gear 33 fixed on a horizontal shaft 34 which is journaled at one end in a bearing 35 on the frame and extends at its opposite end through a bearing 36 on the crank case 4 into axial alinement with the engine shaft 5 within said case. Slidably splined on this end of said shaft is a clutch cone 37 which is normally held 45 yieldably engaged with a clutch cup 38 on the gear 9 of the engine shaft by the tension of a coiled spring 39 interposed between the bearing 36 and a peripherally grooved collar 40 on said cone, the latter being provided 50 with an actuating lever 41 pivoted in the case 4 and carrying exteriorly thereof a foot 55 pedal 42 for manually operating the clutch to control the driving of the auxiliary propeller from the shaft of the engine.
- 60 65 In connection with the above described mechanism for the operation and control of the main and auxiliary propellers the machine may also be provided as usual with suitable steering and controlling means, such as vertical and horizontal rudders, one form

of each of which is indicated at 43 and 44 respectively, the former being shown as connected by cables 45 for operation through the oscillating movement of the pivoted seat 26, and the latter by cables 46 leading to 70 controlling members 47 arranged adjacent said seat for manipulation by the driver. For supporting the machine upon land or water any suitable form of landing gear and floats may be employed.

75 In operating a machine equipped with my improved propelling means as described so as to ascend abruptly from the ground within a limited running space, the main propeller shaft 18 is first tilted or raised upward angularly relative to the body of the machine through the turning of the rock-shaft 13 by rotation of the control shaft 25 with the hand wheel 27, so as to cause the propeller 19 to exert an upward lifting force 80 upon the forward end of the machine. The auxiliary propeller being normally in driving engagement with the engine shaft will be caused to exert an upward lifting force upon the rear end of the machine simultaneously with the application of the power of the engine to drive the main propeller, hence the machine will be caused to rise bodily and quickly within a comparatively short longitudinal space. When the desired altitude 85 has been reached with the propellers operating as above described, the main propeller may be returned to its normal substantially horizontal position by a reverse operation of the hand wheel 27, and the auxiliary propeller may be released from the driving power by depressing the foot pedal 42 to retract the clutch 37 and disconnect the shaft 34 from driving engagement with the engine when the machine will be caused to travel 90 horizontally forwardly under the power of the main propeller in the usual manner.

95 In addition to the use, as is common, of tail rudders and elevators for steering and controlling the course of the machine, the auxiliary propeller may be operated to assist in elevating the tail of the machine when desirous of quickly deflecting the course of the machine downwardly, and when descending the uses of this propeller in conjunction 100 with the main propeller in the upward tilted position will serve to check the descent and enable a gradual landing of the machine to be made within a comparatively small space.

105 What I claim is:

110 1. In an airplane, the combination with the planes and body of the machine, of an engine mounted thereon, a vertical shaft in driving engagement with said engine, a rock-shaft in transverse alinement to said vertical 115 shaft, a main propeller shaft journaled at one end in said rock-shaft and at its opposite end in an arcuate guide-way and adapted to swing with the movement of said rock-shaft vertically in the arc of a circle 120 125 130

about the axis of said shaft to angular positions relative to said planes, driving connections between said vertical shaft and said propeller shaft operative at all positions of the latter, manually controlled means for actuating said rock-shaft, an auxiliary horizontally rotatable propeller mounted upon a vertical axis intermediate the ends of said machine, and driving connections between 10 said auxiliary propeller and said engine.

2. In an airplane, the combination with the body of the machine, of an engine mounted on said body and having a gear case extension thereon, a rock-shaft journaled in said gear case and carrying a loose gear thereon, a driving connection between said gear and the shaft of the engine, a main adjustable propeller shaft loosely received at one end transversely in said rock-shaft and journaled in bearings mounted to move in arcuate guides concentric to the axis of said rock-shaft, a driving connection between said loose gear and said propeller shaft operative in all positions of the latter,

a gear fixed on said rock-shaft, a control shaft journaled in said gear case in driving engagement with said fixed gear for imparting movement to said rock-shaft to adjust said propeller, and an auxiliary horizontally rotatable propeller operatively associated 30 with said engine and adapted to be driven simultaneously with said main propeller in any of its adjusted positions.

3. In an airplane, the combination with the planes and body thereof, of an engine mounted thereon, a vertical shaft driven by the engine, a rock shaft transverse to said vertical shaft, a propeller shaft transverse to said rock shaft and journaled at one end therein, means for guiding the propeller shaft in an angular movement actuatable by the rock shaft, a driving connection between said vertical shaft and the propeller shaft operative in all positions of the latter, and means for actuating the rock shaft. 45

In testimony whereof I sign this specification.

FRANK J. BAUMAN.
